[57] **CLAIM**

The ornamental design for a cabinet door, as shown and described.

DESCRIPTION

FIG. 1 is a front elevational view of a cabinet door, showing my new design;

FIG. 2 is a side elevational view thereof.

FIG. 3 is an end elevational view thereof.

FIG. 4 is a back elevational view thereof.

FIG. 5 is a cross-sectional view thereof taken along line 5—5 of FIG. 1.

FIG. 6 is a front elevational view of another door or drawer front showing another embodiment of my new design.

FIG. 7 is a side elevational view thereof.

FIG. 8 is an end elevational view thereof.

FIG. 9 is a back elevational view thereof.

FIG. 10 is a cross-sectional view thereof taken along line 10—10 of FIG. 6.
